Des. 216,214
Patented Dec. 2, 1969

216,214

BUTTER DISH OR THE LIKE

Robert Daenen, Erembodegem, Belgium, assignor to
Dart Industries Inc., a corporation of Delaware

Filed Mar. 18, 1969, Ser. No. 16,306

Term of patent 14 years

Int. Cl. D7—01

U.S. Cl. D44—5

FIG. 1

FIG. 2

FIG. 3

FIG. 4

FIG. 6

FIG. 5

FIG. 1 is an exploded perspective view of a butter dish or the like showing my new design;

FIG. 2 is a top plan view of the tray member;

FIG. 3 is a top plan view with the cover in place;

FIG. 4 is a bottom plan view;

FIG. 5 is an exploded side elevational view; and

FIG. 6 is an exploded end elevational view.

The pebbled surface as shown in FIG. 1 is only partially indicated in FIG. 2 for convenience of illustration.

I claim:

The ornamental design for a butter dish or the like, as shown and described.
